UNITED STATES PATENT OFFICE.

JAMES V. RIDGWAY, OF HINSDALE, ILLINOIS.

DESIGN FOR A PICTURE-FRAME.

SPECIFICATION forming part of Design No. 29,285, dated August 30, 1898.

Application filed August 3, 1898. Serial No. 687,641. Term of patent 3½ years.

To all whom it may concern:

Be it known that I, JAMES V. RIDGWAY, a citizen of the United States, residing at Hinsdale, in the county of Du Page and State of Illinois, have invented and produced a new and original Design for a Picture-Frame, of which the following is a specification.

In the drawings, Figure 1 is an elevation, and Fig. 2 a section at the line x x of Fig. 1. This picture-frame is oval, and the leading feature of this design consists of the wreath, eagle-head, and wings above and flags below, as shown.

The picture-opening A has at the sides the

wreath designs B, and above the head C and wings D of an eagle design, and gun, drum, sword, anchor-head, and cannon designs, as represented, and at the base are the flag representations E.

I claim—

The design for a picture-frame substantially as described and shown.

Signed by me this 28th day of July, 1898.

JAMES V. RIDGWAY.
